UNITED STATES PATENT OFFICE.

GEORGE E. NERNEY, OF ATTLEBORO, MASSACHUSETTS.

DESIGN FOR A BROOCH, PIN, BUCKLE, OR SIMILAR ARTICLE.

41,181.

Specification for Design.

Patented Feb. 21, 1911.

Application filed December 30, 1910. Serial No. 600,181. Term of patent 3½ years.

To all whom it may concern:

Be it known that I, GEORGE E. NERNEY, a citizen of the United States, residing at Attleboro, in the county of Bristol and State of Massachusetts, have invented a new, original, and ornamental Design for a Brooch, Pin, Buckle, or Similar Article, of which the following is a specification, reference being had to the accompanying drawing, forming part thereof.

The figure is a plan view of a brooch, pin, buckle or similar article, showing my new design.

I claim:

The ornamental design for a brooch, pin, buckle or similar article as shown.

GEORGE E. NERNEY.
